DESIGN FOR A DOOR HANDLE OR ANALOGOUS ARTICLE

Frederick C. Ruppel, Grand Rapids, Mich., assignor to W. B. Jarvis Company, Grand Rapids, Mich.

Application February 27, 1936, Serial No. 61,391

Term of patent 7 years

To all whom it may concern:

Be it known that I, Frederick C. Ruppel, a citizen of the United States, residing at Grand Rapids, in the county of Kent and State of Michigan, have invented a new, original, and ornamental Design for a Door Handle or Analogous Article, of which the following is a specification, reference being had to the accompanying drawing, forming part thereof, in which:

Fig. 1 is a side elevation,
Fig. 2 is a front elevation, and
Fig. 3 is a sectional view taken on a transverse line substantially through the central portion of the handle embodying my new design.

I claim:

The ornamental design for a door handle or analogous article, as shown and described.

FREDERICK C. RUPPEL.
